ADJUSTABLE EXTENSION GRIP

Daryel C. Zutter, 1203 Washington Ave.,
Toppenish, Wash. 98948

Filed Mar. 30, 1970, Ser. No. 22,084

Term of patent 14 years

Int. Cl. D8—02

U.S. Cl. D8—29

FIG. 1

FIG. 2

FIG. 1 is a left front perspective view of the adjustable extension grip embodying my new design;

FIG. 2 is a right rear perspective view with the extensible member in an alternative position.

I claim:

The ornamental design for an adjustable extension grip, substantially as shown and described.
